UNITED STATES PATENT OFFICE.

WILLIAM F. IRRGANG, OF WINDSOR LOCKS, CONNECTICUT, ASSIGNOR TO GEORGE P. CLARK COMPANY, OF WINDSOR LOCKS, CONNECTICUT, A CORPORATION OF CONNECTICUT.

LIFTING-TRUCK.

1,253,178.

Specification of Letters Patent.

Patented Jan. 8, 1918.

Application filed April 20, 1916. Serial No. 92,400.

To all whom it may concern:

Be it known that I, WILLIAM F. IRRGANG, a citizen of the United States of America, residing in Windsor Locks, in the county of 5 Hartford and the State of Connecticut, have invented certain new and useful Improvements in Lifting-Trucks, of which the following is a specification.

This invention relates to improvements in 10 trucks of the lifting type and particularly to improvements in trucks of the class disclosed in U. S. Letters Patent No. 1,174,580, granted to me March 7, 1916.

Trucks of the type, such as disclosed in 15 the above-mentioned patent, for example, comprise, in general two relatively movable frames, one of which is movably mounted on the other and arranged to receive a load and the other to be wheel supported; lifting mechanism to interconnect the two frames; and devices operable from the truck handle to actuate said mechanism.

An object of this invention is to generally improve the structure and arrangement of 20 the handle operated devices and the lifting mechanism actuated thereby, characterized by provision for relatively slow rate of lift at the start and end of the stroke of the handle and by a larger and substantially 25 uniform rate of lift intermediate these positions, whereby the work required by the operator is distributed throughout the stroke of the handle and the greatest effort is required when the handle is so positioned 30 that the operator can conveniently and efficiently exert his best efforts thereon.

Another object of the invention is to provide in a lifting truck of the type described, improved mechanism whereby the handle 35 operated devices may be connected and disconnected from the lifting mechanism in a simple and efficient manner, with a minimum of time and effort on the part of the operator.

40 Other objects and advantages will appear in the detailed description to follow and in the annexed claims.

Referring to the drawings as illustrating 45 one preferred embodiment of the invention—

50 Figure 1 is a side elevational view of the

truck with the movable frame thereof shown in lowered position;

Fig. 2 is a front elevational view of Fig. 1;

Fig. 3 is a sectional elevation taken on 55 the line 3—3 of Fig. 2 and looking in the direction of the arrows, the hook arm being purposely shown in engagement with the lifting mechanism;

Fig. 4 is a sectional elevation of the truck 60 taken similarly to Fig. 3 and showing the movable frame in raised position;

Fig. 5 is a sectional plan view taken on the line 5—5 of Fig. 3 and looking in the direction of the arrows; 65

Fig. 6 is a view generally similar to Fig. 3 showing a modification; and

Fig. 7 is a diagrammatical view illustrative of the rate of lift of the platform.

A frame 1 formed of a single bar bent 70 into U-form has its cross piece bolted to the rear axle 2', as clearly shown in Fig. 4. The side portions of the U-shaped frame 1 extend forwardly in spaced relation and are bolted, as shown in Figs. 1 and 4, to 75 an arched casting 3. Wheels 2 mounted upon axle 2' support the frame 1 at the rear while the forward end of the latter is supported by a single front wheel 5 which is mounted in a casting 4 swiveled in the 80 arched member 3. The mechanism so far described is a wheel supported frame and may be considered as a carriage upon which the remaining devices to be described are 85 mounted.

A load bearing frame 6, formed in U-shape, as indicated in Figs. 1, 2, 4, and 5, is supported from the frame 1 by pairs of links 7 and 8. This movable frame, when in lowered position, as shown in Fig. 1, is 90 arranged to rest upon the frame 1, whereby its downward movement is limited. The forward pair of links 8 have portions extending above the frame 6 and between these spaced links is a cross-bar 9 by means of 95 which the links may be operated to raise the movable frame 6 in a manner to be described.

The structure just described is substantially the same as that disclosed in my 100

above-mentioned prior patent and has been herein described only in general terms sufficiently to permit an understanding of the improvements to be described. For a more 5 complete detailed disclosure of the general structure and operation of the truck, reference is made to the above-mentioned patent. The present invention is more particularly concerned with an improved arrangement of 10 the truck handle, hook arm, and cross bar 9 for coöperative relation in an improved manner and with improved mechanism, whereby the hook arm may be connected and disconnected with the cross bar 9 in a 15 new, efficient, and convenient way by the operator.

The swiveled frame 4 extends upwardly through and above the member 3 and has a circular flange 10 to support the latter, as 20 shown in Figs. 3 and 4. The upper portion of the frame 4 extending above member 3 is formed with a pair of spaced ears 11 (Figs. 2 and 5) between which a steering and drawing handle 12 is pivoted on a pin 13. 25 The latter extends beyond ears 11 on either side thereof and overlies the upper surface of member 3 in closely adjacent relation, as best shown in Figs. 2 and 5, whereby relative displacement of members 3 and 4 is 30 prevented in a simple and advantageous manner.

Handle 12 has a centrally formed opening near its lower end (Figs. 2 and 5) to receive a hook arm 14 together with mechanism to 35 connect and disconnect the hook with the cross bar 9. The hook arm 14 is pivoted on a pin 15 which, when the parts are positioned as in Figs. 1 and 3, lies closely adjacent the pivot 13 in the rear thereof and 40 substantially in the same horizontal plane. The cross bar 9 is arranged closely adjacent the pivotal connections of links 8 to frame 6 and substantially vertically thereabove, when the frame 6 is in lowered position. 45 The hook arm 14 is adapted to engage the cross bar 9, when released by means to be described, and by this engagement and a downward sweep of handle 12 to move links 8 and thus raise frame 6 from the position 50 shown in Fig. 3 to that shown in Fig. 4. It is to be noted that, when the parts are positioned as shown in Fig. 3, the hook arm pivot 15 lies substantially in a straight line drawn between the handle pivot 13 and the 55 cross bar 9 and that, when the parts are moved to the position shown in Fig. 4, the cross-bar 9 lies substantially in a straight line drawn between the pivot 15 and the fulcrum for link 8. 60 The latter is movable, as disclosed in the above-mentioned patent, in slots formed between the sides of member 3 and frame 1 (see Fig. 5) and is fulcrumed on a rod 16 which extends entirely across member 3 and

substantially abuts the side bars 1, whereby 65 lateral displacement of the fulcrum rod 16 is prevented in an advantageous and simple manner. The links 8 are movable through the arc prescribed by the limits of these slots from the position shown in Fig. 3 to that 70 shown in Fig. 4. In the latter position cross bar 9 abuts spaced surfaces 17 (Figs. 4 and 5) on member 13 which surfaces prevent further clockwise movement of links 8. Since the pivotal connections of the latter 75 lie to the right of fulcrum 16, counterclockwise movement of links 8 is prevented and the frame 6 is positively held by the weight of frame 6 and its load in raised position. When frame 6 is positioned, as in Fig. 1, 80 it rests upon the upper edges of frame 1 at the forward end and upon bosses on links 7 in substantially the manner described in my prior patent above identified.

The improved means for the connection 85 and disconnection of hook arm 14 with cross bar 9 will now be described. The hook arm is fork-shaped adjacent its pivot 15 and encircling the latter and connecting the walls of the hook arm is a boss 19 which has a projection 20 formed thereon as well as two smaller rounded projections 21 and 22. Pivoted at 23 to one side of and within the slot in handle 12 is a latch 24 which is adapted to normally engage the projection 20 and 90 hold the hook arm 14 to handle 12, as shown in Figs. 1 and 6. Latch 24 has a foot piece 25 extending forwardly from handle 12 for convenient actuation by the operator, preferably with the foot. Pivoted at 26 below 100 and in the path of latch 24 is a crank arm 27 which has an integral operating handle 28 extending upwardly therefrom and provided with a cross piece 29 for convenient actuation by the operator. Handle 28 is cut 105 away in Figs. 3 and 4 as it lies in front of the line 3—3 in Fig. 2, but it has been indicated by dotted lines for the sake of clearness. The latch 24 is offset, as shown in Fig. 5, to clear the upstanding handle 28 110 and is adapted normally to rest against the hub of arm 27 as a stop. Arm 27 is forked, as shown in Fig. 2, and pivoted to this forked end at 30 is a finger 31 which has a rounded socket to engage either of the 115 rounded projections 21 or 22 depending on whether hook arm 14 is positioned, as shown in Fig. 4 or Fig. 3, respectively. A spring 32 connects the finger 31 to the latch 24 and normally holds the finger against a stop 33 120 on arm 27. Spring 32 permits relative movement of finger 31 with respect to arm 27 so that the former may, when desired, engage with the projection 21 or 22. It is to be noted that spring 32 acts to yieldingly 125 hold three members in position, namely, the finger 31, so that it abuts stop 33, the arm 37, so that cross piece 29 abuts the front

edges of handle 12, and the latch 24, so that it abuts the hub of arm 27. Thus, the several members of the controlling mechanism for hook arm 14 are held in position 5 efficiently and advantageously by a single spring.

If desirable, the arm 27 may be arranged for manual instead of foot operation, as shown in Fig. 6. This figure is similar to 10 Figs. 3 and 4 except that arm 27 and finger 31 are not shown in section. Adjacent one edge of arm 27 (in substantially the same location as lever 28, as shown in Fig. 2) is an integral upstanding web 40. Slidable within handle 12 is a rod 42 which is connected by a link 41 to the web 40. Rod 42 is offset, as shown at 43, in order when depressed to 15 limit the upward movement of rod 42 by engagement with the upper surface of the opening in handle 12, and thus arm 27 is held positioned by spring 32 in an analogous manner to that already described. Upon depression of rod 42, arm 27 may be 20 swung on its pivot to actuate finger 31 in a manner similar to that already described.

The operation of the truck will now be 25 fully described. The handle 12 and hook arm 14 are normally held in the position shown in Fig. 1 by the abutment of surface 30 of the handle with an upper face of member 3 and by the latch 24, respectively. Hook arm 14 is so pivoted that, when latch 24 is released by pressure on foot piece 25, it drops into operative engagement with 35 cross rod 9. Thereafter, a downward sweep of handle 12 will operate links 8 in an obvious manner and lift frame 6 to the position shown in Fig. 4 wherein it is held 40 by the means already described. If the hook arm 14 is to be disconnected from rod 9 (see Fig. 4) the operator imparts a sharp kick to the cross piece 29 or, if the structure shown in Fig. 6 is employed, depresses 45 rod 42, which moves arm 27 and thus finger 31 so that the latter engages projection 21 and swings hook arm 14 upwardly on its pivot and throws it, through projection 20, into engagement with latch 24, whereby it 50 is held to the handle. The truck may then be drawn and steered by the latter in the usual manner. To subsequently lower the frame 2, the handle 12 may be swung upwardly to substantially normal position and 55 foot piece 25 depressed as before to allow the hook arm 14 to drop on the cross bar 9. The arm 14, obviously, does not immediately become operatively connected to bar 9, as heretofore, but the under surface of arm 14 60 is so fashioned that a downward sweep of handle 12 will draw arm 14 along rod 9 and cam the hook upwardly and allow it to drop into engagement with the cross bar 9 in an obvious manner. It is not necessary, how-

ever, to raise handle 12 to its normal position in order to connect the hook 14 with cross bar 9, and an operative connection may be made simply by depressing the foot piece 25. The rounded end of latch 24 is arranged, when depressed, to engage the inclined surface 60 of hook 14, whereby the latter may be moved to a position wherein it will fall by gravity into operative engagement with cross bar 9. A subsequent upward sweep of handle 12 will lower frame 6 70 and bring the parts into the relative positions shown in Fig. 3. Projection 22 is now positioned in the path of finger 31 so that, as cross piece 29 or rod 42 is depressed, arm 14 is thrown upwardly into engagement with 75 latch 24 in a manner analogous to that already described. It is to be noted that the cross piece 29 of handle 28 always remains in the same position relatively to handle 12 irrespective of the hook 14 so that the part 80 29 is always positioned for convenient operation. Thus, the hook arm may be connected to and disconnected from rod 9 in an improved and efficient manner as desired by the operator manipulating the parts provided for this purpose. 90

The particular arrangement and relative disposition of the handle 12, hook 14, and links 8 together with the pivots 9, 13, 15, and 16 is important since advantages are obtained, which relate to the easy and efficient lifting of a load by manipulation of handle 12 and its associated mechanism. As above described, the hook pivot 15 lies substantially in a line connecting rod 9 and 95 handle pivot 13, when the frame 6 is in lowered position. In fact, pivot 15 is slightly above this line so that the first movement of handle 12 downwardly results in an immediate movement of links 8. The latter, however, move slowly at the start as obviously the horizontal component of a given angular movement of the "arm" from pivots 13 to 100 15 is relatively small at this time. This horizontal component, effective through hook 14, to move links 8, gradually increases so that the links 8 are moved more rapidly at the latter part of the downward sweep of handle 12. The lift of frame 6 is not, however, uniform for uniform angular movements of 105 link 8, but on the contrary is more rapid at the start and gradually decreases to a minimum when the pivotal connection of link 8 with frame 6 directly overlies pivot 16. Thus, the links 8 are moved slowly at the 110 start but at this time a small angular movement of the links causes a relatively large vertical lift of frame 6. Moreover, as the angular movement of links 8 become more rapid, as the handle 12 is swept downwardly, 115 the vertical lift of frame 6 for given angular movements of the links decreases. Thus, at the start relatively slow angular speed of

links 8 is offset by relatively fast vertical lift for a given angular movement and at the end the relatively fast angular speed of links 8 is offset by the relatively slow vertical lift 5 for a given angular movement. Thus, the non-uniform angular speed of link 8 is balanced against the non-uniform vertical lift so that the two work in compensatory relation.

10 The practical result of the arrangement just described is shown in Fig. 7 in the form of a curve 45 which is plotted against vertical lift of frame 6 as ordinates and uniform angular movements of handle 12 as 15 abscissæ. From this curve, it will be seen that the two non-uniform factors above described substantially balance one another except at the immediate start and end of the sweep of handle 12, so that the curve 45 20 coincides with the dot and dash line 46 (indicating uniform lift for uniform angular movements of handle 12) for the greater part of the sweep of the handle.

Thus, the work required from the operator is distributed throughout the sweep of the handle, as distinguished from the general practice in trucks heretofore when frequently, the greater part of the effort was required at the immediate start of the sweep 30 of the handle and gradually decreased to a minimum near the end of the stroke. Generally, the lifting trucks heretofore employed have been arranged as just described and are in consequence hard to start. The 35 improved arrangement, however, makes starting easy and, as a substantially uniform effort is required throughout the stroke of the handle, the operator's work is distributed rather than localized.

40 The invention has been described for illustrative purposes in a single preferred embodiment. The scope of the invention, however, is particularly pointed out in the appended claims.

45 What I claim is—

1. A lifting truck, comprising, a carriage, a handle therefor, a hook arm pivoted at the lower part of the handle, a load lifting mechanism connected to said carriage having means for temporary engagement by said hook and operable by such engagement and a downward sweep of the handle to lift a load, and mechanism associated with the handle and operable independently of the 50 movement of the latter and at the will of the operator to disengage said hook arm, said last-named mechanism constructed and arranged to normally remain in the same relative position with respect to the handle 55 irrespective of the movements of the latter and said hook arm.

2. A lifting truck, comprising, a carriage, a platform, means connecting the carriage and platform operable to lift the latter, a

pivoted handle on the carriage, an arm pivoted to the handle having a hook to engage and operate said means by movement of the handle, said means and hook arm being constructed and arranged so that the latter has a tendency to fall into engaging position 65 with the former, and mechanism structurally independent of said hook and movable independently of the handle at will to remove the arm from engagement with said means, and releasable means to hold said arm out 70 of hook engaging position.

3. A lifting truck, comprising, a carriage, a pivoted handle at the front thereof, a hook arm pivoted at the lower part of the handle, a load lifting mechanism connected to said carriage having means for temporary engagement by said hook, a device normally holding the latter out of engagement with said means and releasable at the will of the operator, said means and hook arm being 80 constructed and arranged so that the latter, when released, falls into engagement with the former, said hook arm being operable by a downward sweep of the handle to lift a load, and mechanism associated with the handle and operable independently of the latter at the will of the operator to engage the hook arm when said lifting mechanism is in raised or lowered position, whereby 85 said hook arm may be disengaged from said means and thrown into engagement with said device.

4. A lifting truck, comprising, a carriage, a pivoted handle at the front thereof, a hook arm pivoted near the lower end of the handle, a load lifting mechanism connected to the carriage having means for said hook arm to engage and devices mounted for independent movement within the handle and adapted to engage said arm, all constructed 100 and arranged so that a downward sweep of the handle may operate said mechanism and the hook may be disengaged therefrom by actuation of said devices by the operator, said devices arranged to normally remain in 105 the same relative position with respect to the handle irrespective of the movement of said hook arm, whereby said devices are positioned at all times for convenient operation.

5. A lifting truck, comprising, a carriage, a handle pivoted at the front end thereof, a load lifting mechanism connected to the carriage, a hook arm pivoted to the handle and adapted to connect with and operate 120 said mechanism by movement of said handle on its pivot, the pivotal connection of said hook arm being in the rear of and substantially in the same horizontal plane as the handle pivot when the handle is up, a 125 latch on the handle adapted normally to hold the hook from movement on its pivot, said hook arm being constructed to auto-

- matically engage said mechanism when the handle is up and the latch is released, and a device structurally independent of said hook arm and operable independently of the handle when the latter is raised or lowered to disengage said hook arm from said mechanism and throw it into engagement with said latch, the latter and said device constructed and arranged for actuation by the operator to cause the connection and disconnection of said hook arm.
6. A lifting truck, comprising, a carriage, a handle pivoted at the front end thereof, an arm pivoted at one end to said handle and formed at its other end with a hook, a load lifting mechanism connected to the carriage having means for temporary engagement by said hook and operable by such engagement and a downward sweep of the handle, to lift a load, a latch pivoted to the handle and arranged to normally hold said arm from movement on its pivot, said arm and means being constructed and arranged so that the former, when the latch is released, falls into engagement with the latter, and means to disengage said arm and throw it into holding engagement with said latch, said last-named means comprising a crank arm pivoted to the handle, and arranged for actuation by the operator, a finger pivoted to said crank arm and yieldably held in engagement therewith, and projections formed on said hook arm and arranged so that one or the other thereof lies in the path of said finger when the handle is raised or lowered respectively, all constructed and arranged for the connection and disconnection of said hook arm by and at the will of the operator.
- 40 7. A lifting truck, comprising, a carriage, a platform, means connecting the carriage and platform operable to lift the latter, a pivoted handle on the carriage, an arm pivoted to the handle having a hook to engage and operate said means by movement of the handle, said means and hook arm being constructed and arranged so that the latter has a tendency to fall into engaging position with the former, a latch pivoted to the handle and arranged to normally hold said hook out of engaging position, a crank arm pivoted to the handle, a finger pivoted to said crank arm and arranged to disconnect said hook arm from said means and throw it into engagement with said latch, a stop on said crank arm engageable by said finger, the crank arm having a part to engage the handle to form a stop for the crank arm and a part arranged in the path of the latch to form a stop therefor, and a spring connecting said latch and finger and arranged to normally hold the latch, crank arm, and finger against their respective stops and to permit independent movement of each away from their respective stops, said crank arm and latch arranged for manipulation by the operator to cause the connection and disconnection of said hook arm and means, as desired.
- 45 8. A lifting truck, comprising, a frame, and a platform, each formed of a single U-shaped bar, a rear axle fastened to the cross piece of said frame on which the rear wheels are mounted, an arched member connecting the open ends of said frame having vertical slots between said member and the side bars of the frame, links pivoted on the rear axle and to said platform, other links connecting the frame and platform movable in and limited by said slots, a rod mounted in said member and extending entirely thereacross on which the last-named links are pivoted, said rod being held from lateral displacement by the side bars of said frame, and a truck handle operated means to swing said links on their pivots, whereby the platform may be raised and lowered.
- 50 9. A lifting truck, comprising, a frame and a platform, each formed of a single U-shaped bar, means fastened to the cross piece of said frame on which rear wheels are mounted, an arched member connecting the open ends of said frame, links horizontally pivoted at their lower ends to the four corners of said frame, and at their upper ends to said platform, a frame swiveled to said member in which a steering wheel is mounted, a flange formed on said frame to support said member, ears formed on said swiveled frame extending above said member, a handle mounted between said ears, a pivot rod for the latter projecting beyond the ears over and closely adjacent said member, whereby relative movement between the latter and said swiveled frame is prevented, and means associated with and operable by the handle to swing said links on their pivots, whereby the platform may be raised or lowered.
- 55 10. A lifting truck, comprising, a carriage, a platform, links pivotally connecting the carriage and platform at the four corners of the truck, a cross rod connecting the upper ends of the forward pair of links closely adjacent their pivotal connection with the platform, a handle pivoted to the carriage, and a hook arm pivoted to the handle and arranged for temporary engagement with said cross rod, the pivot for said hook arm normally lying behind the handle pivot and substantially in a straight line between the latter and said cross rod, said hook operable by a downward sweep of the handle to swing said links on their pivots and raise said platform, said cross rod when the latter is raised lying substantially in a straight line between the hook arm pivot and the fulcrum for the cross rod links, all constructed

and arranged so that the rate of lift of the platform is substantially uniform for uniform movements of said handle.

11. A lifting truck including a lifting mechanism, a pivoted handle to draw and steer the truck and having mounted at the lower end thereof means to connect the han-

dle with said mechanism, when desired, said means including a pivoted hook arm, a latch to hold the latter normally out of position and a structurally independent manually operable lever to move the hook arm to latched position. 10

WILLIAM F. IRRGANG.
